RIVETING DEVICE

Howard Milton Johnston, Toronto, Ontario, Canada, assignor to Massey-Harris Company, Limited, Toronto, Ontario, Canada

Application December 19, 1936, Serial No. 116,832

4 Claims. (Cl. 81—38)

This invention relates to a riveting device and more particularly to a riveting device which may be conveniently operated in association with a vise of usual construction.

It is frequently necessary for users of various types of machinery to replace certain riveted members therein. It is usually difficult for such users to effect a convenient and satisfactory riveting operation with the type of equipment available. For instance, the replacement of the cutting sections in the knife of a mowing machine is necessarily a somewhat frequent operation in which difficulty is experienced.

It is thus an object of this invention to provide a simple riveting device which may be operated by attachment to a vise of usual construction and by means of which riveting operations may be quickly and satisfactorily carried out.

The invention will be described with reference to the accompanying drawing in which

Figure 1 is a side elevation,

Figure 2 an end elevation, and

Figure 3 a plan of a vise with the device in place.

The riveting device will be described in association with a vise and comprises a rigid frame adapted to be secured to a fixed jaw of the vise and carrying a riveting jaw and a lever pivoted to the frame and carrying a cooperating riveting jaw, the lever being arranged to be actuated by a movable jaw of the vise. The riveting jaws are substantially offset with respect to the vise jaws whereby the force exerted on the riveting jaws by the movable jaw of the vise through the lever is greatly increased.

In the drawing, the vise of usual construction comprises a base 1 suitably anchored to a bench 1', a fixed jaw 2 at one end of the base, a movable jaw 3 having an elongated rear portion 3' slidably mounted on the base, and a screw shaft 4 adapted to move the jaw 3 in the usual manner by means of a handle 5.

The riveting device as shown comprises a frame 6 adapted to be secured to the fixed jaw 2 as by a screw clamp 7 and extending laterally of the jaw, a lever 8 having a pivotal connection 9 with the extended end of frame 6, and a pair of cooperating riveting jaws 10, one of which is carried by the lateral extension of frame 6 and the other of which is carried by lever 8 in substantially offset relation to the vise jaws. Lever 8 is provided with a bearing projection 11 arranged for engagement by the face of movable jaw 3.

Frame 6 consists of an arm 12 adapted to abut to about the face of jaw 2 and having one end 12' bent to

engage one side of the jaw and through which the screw clamp 7 may extend, and a short angle member 13 mounted on the arm 12 and adapted to engage the other side of the jaw and form the other element of the clamp. A top plate 14 may be welded to arm 12 and extend along the top of the jaw to provide a more solid mounting of the frame on the jaw.

The pivotal connection 9 consists of a pair of U-shaped strips 16 pivoted to each other adjacent their ends by means of pins 17. One of the strips 16 is mounted on the laterally extending end of arm 12 and the other strip carries the lever 8.

It will be noted that inward movement of the movable jaw 3 will cause bearing engagement thereof with lever 8 and thus effect closing of the riveting jaws 10 whereby a riveting operation may be carried out.

This offset arrangement of the riveting jaws 20 greatly increases the power ratio as between the vise jaws and the riveting jaws and makes it possible to readily apply, by normal operation of the handle 5, sufficient force to snugly fit the rivet into place with neatly formed heads and the body 25 thereof completely filling the hole in which the rivet is placed. This latter is an important consideration in the formation of a perfect union between the two members, as for example the bar and cutting section of a mower knife and the result 30 is a substantial improvement over that obtained in the usual method employed.

The riveting jaws may be arranged as replaceable units. The attachment itself is readily mounted on and removed from the vise as required. The movable jaw of the vise moving inwardly, as shown, leaves the centre of gravity of the load substantially directly over the anchor point on the bench and insures accuracy of the line of movement of the parts.

I claim:

1. A riveting attachment for a vise comprising a frame, means for anchoring said frame to a vise jaw, said frame when anchored to the vise jaw having a laterally extending portion, a riveting jaw on said portion, a U-shaped bearing member secured to said portion adjacent its outer end, a lever, a riveting jaw thereon and means for pivotally mounting said lever on said bearing member.

2. In a vise having a fixed and a movable jaw, a riveting attachment comprising a frame secured to the fixed jaw and carrying a riveting jaw, a lever spaced from said frame and carrying a second riveting jaw in substantial align- 55

ment with said first riveting jaw, means pivoting said lever to the frame at an intermediate point therebetween, said lever having engagement with the movable jaw whereby movement of the latter will actuate the lever.

3. In a vise having a fixed and a movable jaw, a riveting attachment comprising a frame, means for securing the frame to the fixed jaw, said frame when secured to the fixed jaw having a laterally extending portion, a riveting jaw on said portion, a lever spaced from the frame and adapted to be engaged by the movable jaw, a riveting jaw on said lever in substantial alignment with said first riveting jaw, and means pivot-

ing said lever to the frame at an intermediate point therebetween.

4. A riveting attachment for a vise comprising in combination with the jaws of the vise, a frame, means for anchoring said frame to one of the vise jaws, said frame when anchored to the vise jaw having a laterally extending portion, a riveting jaw on said portion, a lever, a riveting jaw thereon, and a pivotal connection between said portion and lever comprising a U-shaped extension on said portion at its outer end and a U-shaped extension on said lever and pivoted to said first U-shaped extension.

HOWARD MILTON JOHNSTON.
